Patented Oct. 7, 1919.

UNITED STATES PATENT OFFICE.

ARTHUR LOWY, OF NEWARK, NEW JERSEY, ASSIGNOR TO NEW YORK ENGINEERING COMPANY, A CORPORATION OF NEW YORK.

STEAM-BOILER.

1,317,930.

Specification of Letters Patent.

Patented Oct. 7, 1919.

Application filed June 26, 1918. Serial No. 241,923.

To all whom it may concern:

Be it known that I, ARTHUR LOWY, a citizen of the United States, and a resident of Newark, in the county of Essex and State of 5 New Jersey, have invented certain new and useful Improvements in Steam-Boilers, of which the following is a specification.

This invention relates to steam boilers, and has for its object to provide means in a 10 boiler of the water tube and drum type having a longitudinal baffle whereby the tubes can be more evenly heated and dead spaces avoided, as compared with constructions heretofore used.

15 In a boiler having a plurality of drums connected by inclined rows of tubes, and having a baffle midway of the tubes extending from the upper drum toward the lower drum, the bulk of the hot gases follows the 20 shortest path to the stack midway of the tube bank and the drums, so that the outside or end tubes do not get sufficient heat, and the middle tubes get more heat than they can absorb. This results in dead spaces at 25 the ends of the bank and a loss in heating efficiency. This invention provides means for interrupting the flow of gases around the baffle at its middle portion, compelling them to take the longer path to the stack 30 which includes the outer or end tubes of the bank, thus resulting in a more even heating of the entire bank, and better efficiency. In order that the best operating efficiency can be obtained, this additional baffling 35 means is made adjustable during operation of the boiler, since a fixed baffle made in the shop cannot satisfy the changed conditions due to working pressure, character of fuel, draft, etc., found in practice.

40 In the accompanying drawing,

Figure 1 represents an end view of a boiler, partly in section, embodying the invention,

Fig. 2 is a section on the line 2—2 of Fig. 45 1, and

Fig. 3 is a detail view of the adjustable overlapping baffles.

1 represents the fire-box, 2 the lower drum, 3 the upper drum, 4 the tubes, 6 the central 50 stack, and 7 the stationary baffle. This baffle is preferably located parallel to the tubes and between the middle rows midway of the bank of tubes and extends from the upper drum 8 toward the lower drum 2, being

spaced from the latter to provide the lower 55 draft opening 8. The lower edge of the baffle 7 carries an angle edge 10 and the lower drum carries a similar angle edge 11, preferably in the same plane as the baffle 7, and forming a continuation thereof. 60 Mounted to slide on these edges 10, 11, and to be supported thereby, are two or more baffle plates 12, 13, which are cut away so as to overlap as shown in Fig. 3, each carrying an operating rod 15, a handle 16, and 65 stop lug 17, the handles 16 stopping against the casing of the boiler when the plates are at their inner positions, and the lugs 17 preventing separation of the plates. Other forms of adjustable plates, supporting 70 means, and stops may be used instead of those specifically shown.

When the baffles are collapsed to give the widest draft opening, they will preferably 75 cover not over one quarter of the opening. This area is determined relatively to the area of the stack in the design of the boiler, and the fixed baffle 7 and the movable baffles 12, 13 will be so proportioned as to provide 80 the proper area. The baffles 12, 13 have the 85 function of dividing the hot gases so as to deflect them toward the ends where the tubes ordinarily are somewhat cooler than those at the middle owing to the gases taking the shortest path. After the gases pass the baffles 12, 13, they converge in the stack 6, thus resulting in a somewhat longer and more 90 prolonged path of contact of the hot gases with the tubes on both sides of the baffles 7, 12, 13. When the baffles are expanded, they 95 will cover about one-half of the area between the baffle 7 and lower drum 2, giving a range of approximately 50% variation which is sufficient for most uses. While the baffle 7 is shown as midway of the tube 100 bank, it will be understood that it can be located at other points as long as the additional baffles 12, 13, perform the function of deflecting the hot gases to heat the tubes in such manner as to induce the best circulation and to prolong the contact of the hot gases with the tubes. It is thus assured that the gases will not short circuit away from the end tubes, and the diagonal return of the gases toward the stack will insure that 105 all tubes are equally heated when the baffles are properly adjusted. The use of this invention will enable a considerable economy

in fuel to be realized, and it can be easily applied to existing boilers with better results than are at present obtained by fixed baffles. Various modifications and changes may be made without departing from the scope of the appended claims.

What is claimed, is:

1. A boiler having vertically separated drums connected by inclined rows of tubes, a fire box below the upper drum, and baffling means parallel with and between the tubes extending from the upper drum to the lower drum and cut away at opposite corners adjacent the lower drum to provide separated draft openings adjacent the lower drum on the opposite sides of the baffle, and avoiding dead spaces adjacent the end walls.
2. A boiler having separated drums connected by tubes, a baffle comprising a fixed baffle and a collapsible baffle, the said fixed

baffle arranged to form openings adjacent the ends of one of the drums, and the said collapsible baffle arranged to vary said openings to equalize the heating.

3. A boiler having separated drums connected by tubes, a fixed baffle between intermediate rows of tubes extending from one drum toward the other drum, adjustable baffles between the intermediate portion of the fixed baffle and said other drum to form variable openings around said baffle adjacent the ends of said other drum, the said adjustable baffles adapted to collapse one upon the other and a stack located above and between said openings to which the gases converge and pass out.

Signed at New York city, in the county of New York and State of New York, this 24th day of June, A. D. 1918.

ARTHUR LOWY.
